(57) **CLAIM**

The ornamental design for a stool as shown and described.

DESCRIPTION

FIG. 1 is a top perspective view of a stool;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is an exploded, top perspective view of FIG. 1, showing all of the components separated for ease of illustration.

The broken lines depict portions of the stool that form no part of the claimed design. The long, dashed, broken line in FIG. 8 depicts the direction of construction of the separated components in the exploded view and forms no part of the claimed design.

1 Claim, 4 Drawing Sheets

FIG. 1**FIG. 2**

FIG. 3**FIG. 4****FIG. 5**

FIG. 6**FIG. 7**

FIG. 8
